United States Patent Office

Des. 187,943

Patented May 17, 1960

187,943

SIDE HANDLE FOR COOKING UTENSILS

Robert A. Eckersberg and James L. Hvale, Chicago, Ill., assignors to Ekco Products Company, Chicago, Ill., a corporation of Illinois

Application December 16, 1959, Serial No. 58,681

Term of patent 14 years

(Cl. D44—29)

Fig. 1 is a top plan view of a side handle for cooking utensils embodying the present design.

Fig. 2 is a side elevation thereof.

Fig. 3 is a rear end view thereof.

Fig. 4 is a section taken along line 4—4 of Fig. 1.

We claim:

The ornamental design for a side handle for cooking utensils, as shown.
